UNITED STATES PATENT OFFICE

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND

CLASPING-DEVICE FOR BRACELETS

Application filed February 15, 1930. Serial No. 423,801.

This invention relates to improvements in clasps or fastening-devices for connecting the ends of wrist-watch straps, bands, bracelets or the like.

5 One object of the invention is to provide a clasp or fastening-device of simple construction which effects a more secure joiner of the parts of the band or bracelet, and which is proof against unwarranted or accidental unfastening.

10 Another object of the invention is to provide a clasp or fastening-device adapted for use with bands or bracelets composed of cords or the like.

15 Another object of the invention is to provide a device of the type specified which is neat and ornamental in appearance, capable of being manufactured at low cost and proof against derangement or getting out of order 20 in use.

Further objects of the improvement are set forth in the following specification which describes a preferred form of construction of the device, by way of example, as illustrated by 25 the accompanying drawings. In the drawings:

Fig. 1 is a plan view of the present improved clasp-device showing it as applied to use for connecting the ends of a cord bracelet;

Fig. 2 is a side view of the device;

Fig. 3 is a sectional view of the same taken on line 3—3 of Fig. 1 showing the clasp opened;

35 Fig. 4 is a perspective view showing the clasp as disconnected from one of the terminal-members of the band or bracelet; and

Fig. 5 is a perspective view of the clamp for securing the terminal-member to the 40 bracelet.

In accordance with a prevailing mode, wrist-watch straps and bracelets may be composed of twisted or braided cords, leather bands or other flexible straps connected to 45 the bails of the watch and provided with means for clasping their opposite ends around the wrist. The present improved clasp is adapted for this type of bracelet and also for use with metal mesh or link bracelets if de- 50 sired.

In the present drawings the clasp is shown as applied to use on a bracelet composed of double cords, the ends of which are looped for attachment to the wrist-watch. Referring to Fig. 1 of the drawings, the cord bracelet is 55 therein represented as composed of two parallel cords 2 and 3 having their ends gripped in terminal-members 5 which are of the same construction for both sections of the bracelet. Each terminal-member 5 is constructed in the 60 form of a box having a top portion 6 with sides 7 folded downwardly therefrom and continued forwardly in a loop 8 formed with a relatively narrow cross-bar 9. The metal 65 cut from the sides of the loop 8 is bent downwardly in a strip or flap 10 which partly closes the forward end of the terminal-member to give a more finished appearance to this part.

Pivoted between the sides 7 of the terminal-member 5 is a clamp-member 12 consisting of a flat blade or plate having trunnions 13 projecting through holes in the sides. The clamping-plate 12 is provided at its pivoted end with an upturned serrated jaw 14 70 adapted to bite into the end of the strap or band, in this case to engage the ends of the cords 2 and 3 when the clamp is swung into position with its end resting against the edge of the downturned portion 10 of the member 75

5. The lower edge of the flap 10 of the member 5 is formed with a notch 11 through which the point of a suitable instrument may be inserted to pry the end of the clamp 12 downwardly, as shown by dash lines in Fig. 3, 80 to release its jaw 14 from the end of the cords 2 and 3 when it is desired to detach the latter.

The main clasp-element or connector 15 is constructed in the form of a box having a base 16 with side flanges 17 folded upwardly therefrom, and provided at its opposite ends with circular loops 18 and 19 formed by extensions of the base 16. One end loop 18 is bent completely around with its end abutting the edges of the side flanges 17 95 whereby to close the loop; while at the other end the loop 19 has its end spaced away from the curved edges of the side flanges 17 to form a hook. The loop 18 is hooked around the end-bar 9 on one of the terminal-members 5 100

before being bent into closed relation with the sides 17 of the element 15, and the open-ended loop 19 is adapted to be hooked around the end-bar 9 of the terminal-member 5 on the opposite end of the band or bracelet, see Fig. 3. Through this arrangement, one end of the bracelet is permanently fastened to the clasp while the opposite end is adapted to be manually attached to and detached therefrom as required.

The open loop or end-hook 19 has means cooperating therewith to close its opening to lock it in clasped connection with the cross-bar of the terminal-member 5, this means forming one of the features of improvement of the present invention.

The locking-means for the clasp consists in a pivoted element 20 constructed in the form of a cover for enclosing the top and sides of the main element 15. The locking-member 20 is provided with a top plate 21 and side flanges 22 folded downwardly therefrom to overlap the sides 17 of the element 15. A pivot-pin 25 projects through holes in the sides 17 of the element 15 with its ends riveted through holes in the side flanges 22 of the locking-member 20. It is to be especially noted that the member 20 is pivoted to the main element 15 at a point adjacent the opening of the hook 19, the relation of the parts being such that when the member 20 is closed down against the element 15 the forward edge 24 of the top plate 21 is tilted upwardly to lie alongside, in substantially abutting relation to the edge of the beak of the hook 19.

The side-flanges 17 of the element 15 are formed with longitudinal slots 26 and the sides 22 of the member 20 are punched in or indented to form detent-protuberances 27 on their inner faces adapted to snap into the aforementioned slots when the parts are closed together as shown in Figs. 1 and 2. On the rearward edge of the top plate 21 of the member 20 is an upwardly curled lip 28, providing means for lifting the locking-member by inserting the fingernail thereunder. The method of operation of the improved device is as next explained.

The end of each section of the band or bracelet, composed of the two cords 2 and 3 as herein illustrated, is fastened to a terminal-member 5 by inserting it into the hollow portion thereof with the clamp 12 turned back into the position illustrated by dash lines in Fig. 3. The clamp 12 is then swung on its pivots to bring its free end against the bottom edge of the portion 10 of the terminal-member. Under this action the teeth on the jaw 14 of the clamp will bite into the cords to bind them securely within the sides of the terminal-member 5 which thus encloses the ends of the cords and protects them from fraying or ravelling.

The clasp-element 15 is secured to one of the

terminal-members 5, during the process of assembling the parts, by bending its loop 18 around the cross-bar 9 to close its edge against the edges of the side flanges 17 on the member 15.

The other terminal-member 5 is attached to the opposite end of the bracelet length in the same manner with its cross-bar 9 adapted to be engaged with the hook 19 of the element 15 when the locking-member 20 is rocked upwardly into the position illustrated in Figs. 3 and 4. After the bracelet has been placed around the wrist and its ends connected in the manner as above explained the locking-member 20 is swung down against the main element 15 of the clasp with its side flanges 22 overlapping the flanges 17, the detent-protruberances 27 being thus caused to snap into the slots 26 to retain the parts of the clasp in closed relationship. As the free end of the locking-member 20 is swung down against the bottom clasp-element 15 the forward edge 24 of its top plate 21 is tilted upwardly into opposite, abutting relation to the open end of the hook 19 to close the entrance to the hook as shown in Fig. 2. With the locking-member 20 in closed position the loop 8 on the terminal-member 5 will be held against release from the hook 19 and the ends of the bracelet will thus be securely fastened in connected relationship. Any force tending to release the cross-bar 9 on the terminal-member 5 from the hook 19 will serve to maintain the locking-member 20 more firmly in its closed position, rather than to force it open. That is to say, as the cross-bar 9 is forced back toward the entrance of the hook it will engage the forward edges of the sides of the locking-member 20, thus tending to prevent the latter from swinging into open position. Due to this novel construction and arrangement of the parts with the pivot of the locking-member 20 disposed adjacent the opening of the hook 19 and the forward edge of its top plate 21 above the pivot point, the clasp is proof against unwarranted opening and is therefore much more secure than other forms of similar devices where a pull on the bracelet tends to swing the locking-device open.

When it is desired to unclasp the bracelet the fingernail is inserted under the lip 28 of the locking-member 20 to swing the latter upwardly into open position as shown in Fig. 3. The forward edge 24 of the member 20 will thus be tilted downwardly to open the hook to permit the release of the cross-bar 9 therefrom.

It will be observed from the foregoing that the present invention provides a particularly simple yet efficient means for clasping the ends of a band, strap or bracelet to render it secure against accidental or unwarranted unfastening. The clasp proper comprises only two simple elements, the bottom-element 15 and the locking-member 20, and the terminal-

members 5 are likewise of simple construction and economical to manufacture. The complete device is particularly neat and artistic in appearance, having the effect of coupled box-links which conform closely to the shape of the strap or band to which they are applied and occupy a minimum of space. Moreover, the whole device is compact in form and ornamental in appearance with all of its mechanical elements enclosed and concealed from view.

While the device is herein shown as embodied in a preferred form of construction, various modifications may be made in the 15 shape and arrangement of its parts without departing from the spirit or scope of the invention.

Therefore, without limiting myself in this respect, I claim:

20 1. In a device of the type specified, the combination of a clasp-element comprising a bottom portion and upstanding sides with a hook at one end, a connecting-member for engagement with the hook of the clasp-element, 25 a locking-member having a top portion with sides projecting downwardly therefrom to adapt them to straddle the sides of the clasp-element, and means for pivoting the sides of the locking-member to the sides 30 of the clasp-element with the forward edge of its top portion substantially abutting the end of the beak of the hook on the clasp-element and adapted to rock into the opening of the hook to open the latter to receive the 35 connecting-member, the forward edges of the sides of the locking-member normally extending across the hook opening to adapt them to be engaged by the connecting-member to tend to hold the locking-member closed and 40 prevent release of the connecting-member from the hook.

2. In a device of the type specified, the combination of a clasp-element comprising a bottom with sides projecting upwardly at 45 right-angles thereto and a hook at one end formed by an extension of the bottom portion of said element, a locking-member comprising a top plate with sides folded downwardly therefrom to adapt them to straddle the 50 sides of the clasp-element, said locking-member formed with an upwardly curled lip at its rearward end for lifting said member by the insertion of the fingernail thereunder, and a pivot extending laterally through the sides 55 of the locking-member and the sides of the clasp-element to position the locking-member with the forward edge of its top plate abutting the end of the beak of the hook while adapting it to be rocked into the opening of the hook to open the latter to receive a connecting-member, the forward vertical edges of the locking-member normally extending across the hook opening to adapt them to be engaged by the connecting-member 60 to hold said locking-member from cant-

ing or rocking whereby to prevent accidental or unwarranted release of the connecting-member from the hook.

3. In a device of the type specified, the combination of a clasp-element having a bottom with opposite sides projecting upwardly therefrom and a hook at one end formed by an extension of the bottom, a locking-member comprising a top plate with sides folded downwardly therefrom to straddle the sides 70 of the main clasp-element, means for pivoting the locking-member to the clasp-element to adapt the forward edge of its top plate to abut the end of the beak on the hook, detent-protuberances projecting inwardly from 75 the sides of the locking-member, and elongated slots on the sides of the clasp-element adapted to receive the detent-protuberances 80 which snap thereinto to hold the locking-member in closed position.

In testimony whereof I hereunto affix my signature.

CHARLES H. KESTENMAN.
